OSCAR WOODWARD, OF NEW YORK, N. Y., ASSIGNOR TO WYCKOFF, SEAMANS & BENEDICT, OF ILION, NEW YORK, A CORPORATION OF NEW YORK.

TYPE-WRITING MACHINE.

No. 838,495.

Specification of Letters Patent.

Patented Oct. 16, 1906.

Application filed July 9, 1904. Serial No. 215,846.

To all whom it may concern:

Be it known that I, OSCAR WOODWARD, a citizen of the United States, and a resident of the borough of Manhattan, city of New York, 5 in the county of New York and State of New York, have invented certain new and useful Improvements in Type-Writing Machines, of which the following is a specification.

This invention relates to type-writing machines, and more particularly to the ribbon mechanism thereof.

One object of the invention is to provide an efficient lever-actuated means operable from the front of the machine, whereby any 15 of a plurality of inking-surfaces having different colors or characteristics may be readily brought to the operative position, where it will coöperate with the types.

Another object of the invention is to provide 20 means for indicating which one of the plurality of inking-surfaces is in operative position.

To the above and other ends, which will subsequently appear, the invention consists 25 of the features of construction, arrangements of parts, and combinations of devices to be hereinafter more fully described, and particularly pointed out in the concluding claims.

In the drawings illustrating these improvements, Figure 1 represents the upper part of 30 the left-hand end of a type-writing machine, part of the frame being broken away to more clearly disclose my invention. Fig. 2 is a detail perspective view of the ribbon-spools and the guide or carrier. Fig. 3 is a top plan view 35 of certain of the parts illustrated in Fig. 1 and showing the mechanism arranged for automatically producing the lateral feed within one color or section of the ribbon. Fig. 4 is a 40 similar view of the same with most of the mechanism omitted and showing the ribbon shifted for the use of the other color and the shifting-frame held by the locking-spring. Fig. 5 is a side elevation, partly in section, of 45 the shift-lever and its sleeve-bearing and the forward supporting-arm. Fig. 6 is a top plan view of a modification of the invention. Fig. 7 is a side elevation of the modification shown in Fig. 6.

The invention is shown applied to a No. 50 6 Remington machine; but it is to be under-

stood that it may be adapted to other forms of writing-machines.

Considering first Figs. 1 to 4, inclusive, 1 designates a carriage in which is mounted a 55 platen 2, the carriage being arranged to travel above the top plate 3 from side to side of the machine and being propelled by a spring within the carriage driving drum 4 through the agency of a strap or band 5. The drum 60 4 revolves freely on a supporting-shaft 6 and is provided on its front side with a pawl 7, which engages the teeth of a ratchet-wheel 8, also loosely mounted on the shaft 6. With the feeding movement of the carriage 1 from 65 right to left the revolving drum and its pawl 7 turn the ratchet-wheel 8; but when the carriage is returned to its starting-point the drum revolves in the opposite direction, and the pawl 7, failing to act upon the ratchet- 70 wheel 8, leaves it at rest. The ratchet-wheel 8 carries on its hub a beveled gear 9 and a spider 10, the gear 9 engaging a similar beveled gear 11, mounted on the shaft 12. The shaft 12 is employed in this class of type-writ- 75 ing machines as the means by which the ribbon-spools are alternately wound to change the direction of longitudinal feed of the ribbon, and it is not deemed necessary to more fully illustrate this feature of the construc- 80 tion, since it is well known.

As best appears in Fig. 3, the beveled gear-wheel 11 is formed integral with a sleeve 13, which is perforated to receive a second sleeve 14, the two sleeves being secured together by 85 a set-screw 15. The sleeve 13 is loosely mounted on the shaft 12 and is formed with a crank-arm 16, from which extends a pin 17, parallel with the shaft 12. A crank-arm 18 is secured fixedly to the shaft 12 and is pro- 90 vided near its end with a slot or opening through which the pin 17 loosely passes. This construction permits of the longitudinal movement of the shaft 12 independently of the sleeves 13 and 14, the beveled gear 11, 95 and the crank-arm 16, which are held against participation in said movement by brackets 19 19, depending from the top plate and through one of which the sleeve 14 extends. The crank-arms 16 and 18, through the me- 100 dium of the pin 17, rotate together, so that a rotation of the gear 11 may be transmitted to

the shaft 12 irrespective of the longitudinal position of the latter.

The shaft 12, which extends from side to side of the machine, has a beveled gear-wheel 20 secured near its left-hand end, which gear meshes with a similar gear-wheel 21 on a shaft 22. The latter shaft carries the ribbon-spool 23 and is in turn supported in lugs 24, depending from the top plate. It is to be understood that another and similar gear (not shown) is mounted near the opposite end of the shaft 12 for coöperation with the gear of the other ribbon-spool shaft 25, Fig. 2.

The spider 10 is provided with several lugs 26, 26, which project outwardly, and as the ratchet-wheel 8 and the spider 10 revolve they strike the outer end of a lever 27, pivoted on the shaft 28 of the ratchet-wheel 28^a, said shaft being supported in a bracket 29, depending from the under side of the top plate 3. The lever 27 carries a pawl 30, which engages with the teeth of the ratchet-wheel 28^a, and as the lugs 26, 26 strike the outer end of the lever they cause it to rise and fall, the pawl 30 playing in the teeth on said ratchet-wheel, and thereby causing it to slowly revolve and turn its shaft 28 and a worm 32 thereon. The worm 32 engages the worm-wheel 33 on a vertical shaft 34, mounted in the bracket 29, and the shaft 34 bears at its upper end a cam 35, the latter having two steps 36, 36 and a spiral face 37. The cam 35, though differing in detail from that shown in the patent to Diss, No. 599,417, generally resembles the latter and its function is similar. It is therefore not deemed necessary to describe the cam 35 and its operation at greater length.

The left-hand ribbon-spool 23 and the right-hand ribbon-spool 38 slide freely on the shafts 22 and 25; but each spool is caused to revolve with its shaft by means of a spline on the shaft or by any well-known or desired means. The ribbon 39 passes from the left-hand spool up and over a guide-pin 40 and then over the type-basket to the right-hand ribbon-spool. The guide-pin 40, Fig. 2, has its bearings in two ears 41 of a frame 42, and the latter has depending from its under side two fingers 43, which span the associated spool and control its movement along the shaft 22. The frame 42 is carried by two supporting-arms 44 and 45, which are provided with sleeves 46 and 47, said sleeves being perforated to receive the pivot-posts 48 and 49, secured to the under side of the top plate. This method of mounting the supporting-arms affords an easy swinging movement, while the swinging ends of said arms are pivoted to different sides of the shifting-frame 42 and cause it to move fore and aft of the machine during the swinging movement of the arms. This movement is imparted to the arms by means of the short arm 50, pro-

jecting rearwardly from the arm 44 near its pivot and having a forked end which carries a roller 51, designed to ride ordinarily over the face of the cam 35.

Integral with the sleeve 47, which carries the supporting-arm 45 and projecting forwardly at about right angles to the said supporting-arms, is a shifting or switching lever 52, which terminates in a thumb-piece 53, the latter being close to the under side and front edge of the top plate 3. Seated in a depression or cup 54 just to the rear of the thumb-piece is a disk 55 for indicating the color or characteristics of the ribbon-field at the printing-point. A spring 56 is wound about the pivot-post 49 above the sleeve of the supporting-arm 45, and one of its ends bears against the said arm, while the other end bears against the depending rim of the top plate. The spring 56, bearing against the arm 45, tends to force it and the shifting-frame 42, with its supporting-arm, rearwardly and to cause the roller 51 to ride on the face of the cam 35.

The forward end of the guide-pin 40 is threaded to receive the sleeve or nut 57, which is formed with an annular groove 58 for the reception of the wedge-shaped end 59 of a flat spring 60, secured to the top plate by screws 61.

The shifting-frame 42 supports a ribbon guide plate 62 of the usual or any suitable construction, the other end of the said guide-plate being provided with depending arms 63, which control the fore-and-aft movement of the right-hand ribbon-spool 38.

The inking surface or ribbon 39 is provided with two fields 64 and 65. These fields may be inking-surfaces of two different colors—such, for instance, as black and red—or they may have different characteristics. Thus the field 64 may be copying-ribbon, whereas the field or section 65 may be record-ribbon, though for convenience the sections will be referred to as of two different colors—black and red. The black field 64, as here shown, has about twice the width of the red field 65. In Figs. 1 and 3 the ribbon is shown positioned so that the types 66 act on the black field or section of the ribbon, while in Fig. 4 the red section is shown in operative position.

The operation of the mechanism will now be described. The revolution of the ratchet-wheel 8 in the letter-space movement of the carriage from right to left causes the lugs 26 of the spider 10 to strike the free end of the lever 27, and the movement of the pawl 30 on the other end of the said lever, acting on the ratchet 28^a, causes the latter to revolve and with it the worm 32. The worm-wheel 33 is turned by the rotation of the worm 32 and carries with it the cam 35, the face of which causes the arms 50 and 44 to oscillate about the post 48, thereby moving the frame 42 lat-

erally and shifting the spool 23 fore and aft of the machine along the revolving shaft 22. The frame 42, through the ribbon-guide plate 62 and the depending arms or fingers 63, carried thereby, shifts the right-hand ribbon-spool 38 in unison with the left-hand ribbon-spool. The action of the cam 35 shifts the black section of the ribbon laterally over the printing-center during the longitudinal feed of the ribbon and utilizes every portion of it in a manner well understood. The relations of the parts during this operation are best seen in Fig. 3, in which figure, it will be noted, the shifting-lever 52, the thumb-piece 53, and the indicator 55 are covered by the top plate of the machine. It is obvious, therefore, that when the indicator is covered the forward or black section of the ribbon is in the path of the types. The cam 35 is of such dimensions that the fore-and-aft movement of the ribbon while the cam coacts with the roller 51 does not carry the front and rear edges of the black section or strip 64 outside the path of the types.

When it is desired to write upon the rear field or red section 65 of the ribbon, the thumb-piece 53 is pushed to the left of the operator until the wedge-shaped end 59 of the flat spring 60 engages the annular groove 58 in the nut 57. The parts will then be in the position illustrated in Fig. 4. The disk 55 will be exposed to the view of the operator, thus indicating that the section of the ribbon to which it corresponds is in the printing-field. The roller 51 no longer rides on the face of the cam 35 and the shifting action of the ribbon fore and aft of the machine is dispensed with when the red section 65 is in printing position. The operation of the cam-driving mechanism continues, but the roller 51 having been moved out of the path of the travel of the cam the ribbon-carrier is not affected by it. When it is desired to again write on the black field, the thumb-piece 53 is pushed to the right, freeing the ribbon-frame from the locking-spring and again covering the indicating-disk.

In the modified form of the device shown in Figs. 6 and 7 the shifting-lever 67, the indicator 68, and the thumb-piece 69, instead of being formed integral with the arm 45 and sleeve 47, are shown as a separate piece. This piece terminates at the rear in a split collar 70, which is adjustable by means of a screw 71, which passes through ears 72, with which the collar is provided. By this means the piece may be attached to the sleeve 49, as it is ordinarily found in the machine, without altering the construction of the latter in any respect, the split collar 70 surrounding or embracing the sleeve 47. During the operation of these devices it will be observed that the longitudinal feed of the ribbon in either direction is in no way interfered with,

and the change of color or character of the printing-surface is readily effected without touching the ribbon and from a convenient place at the front of the machine. When the ribbon is displaced by another style, the disk 55 may be replaced by one corresponding to the rear section of the new ribbon either in color, by some word or symbol, or the like.

It is to be understood that I do not desire to be limited to the particular construction herein shown, but that various changes may be made without departing from the spirit of my invention.

By the term "multicolored" ribbon I mean two or more inking-surfaces having different colors or characteristics.

What I claim as new, and desire to secure by Letters Patent, is—

1. In a type-writing machine, the combination of a multicolored ribbon, ribbon-spools, means for automatically shifting the ribbon-spools bodily and for automatically revolving them, and independent means for affording a bodily shift of the spools to bring any colored section or field of the ribbon into the path of the types without affecting the means for revolving said spools, said independent means being actuated by a pivoted shifting-lever operable from the front of the machine.

2. In a type-writing machine, the combination of a multicolored ribbon, ribbon-spools, means for automatically shifting the ribbon-spools bodily and for revolving them, independent means for affording a bodily shift of the spools to bring any colored section or field of the ribbon into the path of the types without affecting the means for revolving said spools, and means to indicate what section of the ribbon is in the path of the types.

3. In a type-writing machine, the combination of a multicolored ribbon, ribbon-spools, means for automatically shifting the ribbon-spools bodily and for revolving them, independent means for affording a bodily shift of the spools to bring any colored section or field of the ribbon into the path of the types without affecting the means for revolving said spools, said independent means being actuated by a pivoted shifting-lever operable from the front of the machine, and an indicator that shows which section of the ribbon is in the field of the types.

4. In a type-writing machine, the combination of a multicolored ribbon, ribbon-spools, means for automatically shifting the ribbon-spools bodily and for revolving them, and independent means for affording a bodily shift of the spools to bring any colored section or field of the ribbon into the path of the types without affecting the means for revolving said spools, said independent means being provided with an indicator that shows which section of the ribbon is in the path of the types.

5. In a type-writing machine, the combination of a multicolored ribbon, ribbon-spools, means for automatically shifting the ribbon-spools axially and for revolving them, independent means for affording a bodily shift of the spools to bring any colored section or field of the ribbon into the path of the types, a pivoted shifting device operable from the front of the machine to actuate said independent means, and an indicator on said pivoted shifting device. 10
6. In a type-writing machine, the combination of a multicolored ribbon, ribbon-spools, a shift-lever, means actuated by said shift-lever to bring any colored section of the ribbon into the path of the types, a cup or depression in said lever, and an indicating-disk seated in said cup or depression. 15
7. In a type-writing machine, the combination of a multicolored ribbon, ribbon-spools, a shift-lever, means actuated by said shift-lever to bring any colored section of the ribbon into the path of the types, a cup or depression in said lever, and an indicating-disk seated in said cup or depression, said indicating-disk being capable of being changed to correspond in character with the ribbon-field it indicates. 20
8. In a type-writing machine, the combination of a multicolored ribbon, ribbon-spools, a shift-lever, means actuated by said shift-lever to bring any colored section of the ribbon into the path of the types, an indicator on said shift-lever, and means for covering said indicator when the corresponding field of the ribbon is in non-working position and for uncovering said indicator when the said field is in working position. 25
9. In a type-writing machine, the combination of a multicolored ribbon, a pair of ribbon-spools, a pair of ribbon-spool shafts, a spool-shifting frame for one of said ribbon-spools, a ribbon-guide frame attached to said spool-shifting frame at one end and having at its other end means for shifting the other ribbon-spool, a pair of pivoted supporting-arms attached to said spool-shifting frame, and a shifting-lever arm connected at one end directly with one of said pivoted supporting-arms and being formed with a finger-piece at the other end. 30
10. In a type-writing machine, the combination of a multicolored ribbon, a pair of ribbon-spools, a pair of ribbon-spool shafts, a spool-shifting frame for one of said ribbon-spools, a ribbon-guide frame attached to said spool-shifting frame at one end and having at its other end means for shifting the other ribbon-spool, a pair of pivoted supporting-arms attached to said spool-shifting frame, and a one-piece shifting member carrying an indicator and connected directly with one of said pivoted supporting-arms, said shifting member and indicator being readily removable from the machine. 35
11. In a type-writing machine, the combination of a multicolored ribbon, a pair of ribbon-spools, a pair of ribbon-spool shafts, a spool-shifting frame for one of said ribbon-spools, a ribbon-guide frame attached to said spool-shifting frame at one end and having at its other end means for shifting the other ribbon-spool, a pair of pivoted supporting-arms attached to said spool-shifting frame, a shifting-lever arm connected with one of said pivoted supporting-arms, and an indicator adapted to be covered and uncovered by the action of said shifting-lever. 40
12. In a type-writing machine, the combination of a multicolored ribbon, a pair of ribbon-spools, a pair of ribbon-spool shafts, a spool-shifting frame for one of said ribbon-spools, a ribbon-guide frame attached to said spool-shifting frame at one end and having at its other end means for shifting the other ribbon-spool, a pair of pivoted supporting-arms attached to said spool-shifting frame, a shifting-lever arm connected with one of said pivoted supporting-arms, and an indicator adapted to be covered and uncovered by the action of said shifting-lever, said shifting-lever and said indicator being detachable without interfering with the ribbon-feeding mechanism. 45
13. In a type-writing machine, the combination of a pair of ribbon-spools connected to move laterally in unison, means for automatically revolving said spools whatever their lateral position, a ribbon-spool-shifting frame, an actuating-spring for moving said shifting-frame in one direction, a pair of pivoted arms supporting said shifting-frame, a shifting-lever arm connected with one of said arms, and a locking-spring for holding the shifting-frame when shifted against the tension of said actuating-spring. 50
14. In a type-writing machine, the combination of a pair of ribbon-spools connected to move laterally in unison, means for automatically revolving said spools whatever their lateral position, a ribbon-spool-shifting frame, an actuating-spring for moving said shifting-frame in one direction, a pair of pivoted arms supporting said shifting-frame, a shifting-lever arm connected with one of said arms, a locking-spring for holding the shifting-frame when shifted against the tension of said actuating-spring, and an indicator for indicating that the shifting-frame has been shifted and locked. 55
15. In a type-writing machine, the combination of a multicolored ribbon, means for shifting one or another color into operative position, and for thereafter automatically feeding the same in longitudinal direction, a color-indicator carried by the shifting means, and means for covering said color-indicator when its corresponding color of ribbon is out of operative position. 60
16. In a type-writing machine, the combination of a multicolored ribbon, a pair of ribbon-spools, a pair of ribbon-spool shafts, a spool-shifting frame for one of said ribbon-spools, a ribbon-guide frame attached to said spool-shifting frame at one end and having at its other end means for shifting the other ribbon-spool, a pair of pivoted supporting-arms attached to said spool-shifting frame, and a one-piece shifting member carrying an indicator and connected directly with one of said pivoted supporting-arms, said shifting member and indicator being readily removable from the machine. 65

nation of a multicolored ribbon, ribbon-spools, a shift-lever, means actuated by said shift-lever to bring any colored section of the ribbon into the path of the types, and an indicator adapted to be covered and uncovered by the action of said shift-lever.

Signed at the borough of Manhattan, city

of New York, in the county of New York and State of New York, this 8th day of July, A. D. 1904.

OSCAR WOODWARD.
